UNITED STATES PATENT OFFICE.

ELIZABETH F. VILKOMERSON, OF NEW YORK, N. Y.

HOLDER FOR FOUNTAIN-PENS.

1,241,311.

Specification of Letters Patent. Patented Sept. 25, 1917.

Application filed January 9, 1917. Serial No. 141,458.

To all whom it may concern:

Be it known that I, ELIZABETH F. VILKOMERSON, a citizen of the United States, residing at New York, in the county of New York and State of New York, have invented 5 certain new and useful Improvements in Holders for Fountain-Pens, of which the following is a specification.

This invention relates to article carrying devices and more particularly to pencil and pen carriers, and has for one of its objects the provision of a device of this class that may be attached to a garment and securely hold the article against accidental misplacement.

Another object is the provision of a device comprising a garment engaging member and a pen engaging member and having means for locking the pen engaging member in position on the garment engaging member.

The carrier described herein is an improvement over the carriers described and shown in my United States Patents Numbers 1,133,897, and 1,166,282, granted March 25 30, 1915 and December 28, 1915, respectively, the principal improvement being a locking member and finger engaging means for releasing said locking member.

Other objects and advantages such as simplicity, cheapness in manufacture and the general improvement of the art will be more fully brought out in the following specification and illustrated in the accompanying drawings in which:

Figure 1 is a perspective view of my device,

Fig. 2 is a side view thereof attached to a pen,

Fig. 3 is a rear view thereof attached to a pen,

Fig. 4 is a side view of a modified form of my device, and

Fig. 5 is a front view thereof.

Referring more particularly to the drawings the numeral 1 designates a fountain pen having a member 2 of my device thereon. An ear 3 having an aperture 4 therein is formed on the member 2.

A garment engaging member 5 adapted 50 to receive and hold the member 2 comprises a body portion 6, an upwardly extending

member 7 terminating in a tongue 8. A locking means is formed by a downwardly extending member 9 having a spring formation 10 at its junction with the body portion 55 6. Finger engaging portions 11 extend outwardly at the side of the member 9 and body portion 6.

Lugs 12 are cut from the body portion 6 and bent back and a pin 13 is pivoted therebetween. The pin 13 is adapted to be secured in a catch 14.

The operation of the device is as follows: The member 6 is secured to the garment by the pin 13 and the member 2 is secured to 65 the member 6 by passing the tongue 8 through the aperture 4 in the ear 3. The ear 3 is now locked in position under the member 9.

To release the parts the finger engaging 70 portions 11 are grasped and thus remove the member 9 from the path of the ear 3 and allow its ready removal.

Having thus described my invention what I claim is:

1. A fountain pen holder comprising a pen engaging member, an apertured ear thereon, a garment engaging member, a tongue on said garment engaging member engageable within said ear, and releasable 80 spring locking means on said last named member engaging said tongue.

2. A fountain pen holder comprising a pen engaging member, an ear on said member, a garment engaging member, an upwardly extending tongue formed on said garment engaging member adapted for engagement with said ear, and a spring locking member formed on the upper end of 85 said garment engaging member and extending downwardly in engagement with said tongue.

3. In a fountain pen holder having a pen engaging member and an ear formed on said member, a garment engaging member comprising a plate having its lower end bent upwardly and shouldered to provide a tongue to engage said ear, and its upper end bent downwardly to provide a locking member 95 engaging the rear side of said tongue.

4. In a fountain pen holder having a pen 100 engaging member and an ear on said mem-

ber, a garment engaging member comprising a body portion, an upwardly extending portion thereon terminating in a tongue to engage said ear, a shoulder formed at the 5 base of said tongue, a spring locking member formed on said member and engaging said tongue, and finger engaging projections

formed on said locking member and said body portion to facilitate the releasing of said locking member from engagement with said tongue.

In testimony whereof I hereto affix my signature.

ELIZABETH F. VILKOMERSON.
